(57) **CLAIM**

The ornamental design for a propane fire pit, as shown and described.

DESCRIPTION

FIG. 1 is a front and top perspective view of a propane fire pit showing my new design.

FIG. 2 is a rear and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a folded rear and bottom perspective view thereof.

FIG. 10 is an enlarged view of a portion indicated with "10" in FIG. 1; and,

FIG. 11 is an enlarged view of a portion indicated with "11" in FIG. 1.

The evenly spaced broken lines in the figures illustrate portions of the propane fire pit that form no part of the claimed design. The dot-dash broken lines in FIGS. 1, 10, 11 are for the purpose of depicting the boundary lines of the enlarged views and form no part of the claimed design.
